UNITED STATES PATENT OFFICE

CHARLES A. LEE, OF KANSAS CITY, KANSAS

ENGINE OPERATING DEVICE

Application filed August 22, 1927. Serial No. 214,602.

My invention relates to improvements in engine operating devices.

It is particularly well adapted for use in connection with explosive engines.

5 One of the objects of my invention is to provide, in an engine having a reciprocative piston, novel means for converting the reciprocating movement of the piston into rotary movement.

10 My invention provides further a novel spiral driving mechanism.

My invention provides further novel driving means by which the speed of a driven shaft may be increased without increasing 15 the piston speed, making the invention particularly well adapted for automobile or air plane engines.

20 Still another object of my invention is to provide an engine which is simple, cheap, durable, not liable to get out of order, and which is efficient in its operation.

The novel features of my invention are hereinafter fully described and claimed.

25 In the accompanying drawings, which illustrate the preferred embodiment of my invention,

Fig. 1 is a section, partly broken away, on the line 1—1 of Fig. 2, showing my improved engine, of the explosive type.

30 Fig. 2 is a section of the same, partly broken away, on the line 2—2 of Fig. 1.

Fig. 3 is an enlarged side elevation, partly broken away, of one of the pistons and parts connected therewith.

35 Fig. 4 is an elevation of one of the spirally grooved shafts, the bevel gear thereon being shown in section.

Fig. 5 is a section on the line 5—5 of Fig. 3, the spiral shaft being omitted.

40 Fig. 6 is a section on the line 6—6 of Fig. 7.

Fig. 7 is a top view, enlarged, of one of the driving rings.

Fig. 8 is a cross section on the line 8—8 of Fig. 3.

45 Fig. 9 is a view similar to Fig. 8, the pawl and spring being removed.

Similar reference characters designate similar parts in the different views.

The invention illustrated comprises a two 50 cylinder engine, the cylinders being desig-

nated by 1, 2 the body, 3 the cylinder head having mounted therein the usual intake valves 4 and exhaust valves 5 provided with the usual closing springs 6.

7 designates the usual rocker arms for 55 opening the valves, and 8 the lift rods which actuate the rocker arms 7 and are adapted to be lifted by any suitable known valve operating means which is operable by the engine crank shaft 13 rotatably mounted in the 60 body 2 below the cylinders 1, Figs. 1 and 2.

14 designates the crank case, and 15 a horizontal driven shaft rotatably mounted in the body 2 and extending through the crank case 14. 16 designates a fly wheel which is 65 fastened on the shaft 15 at the outer side of the casing 14.

17 designates the two pistons respectively reciprocative in the cylinders 1, which are respectively connected by connecting rods 18 70 to two cranks 19 of the horizontal crank shaft 13 which is disposed at one side of the central vertical plane of the cylinders.

Rotatably mounted in the body 2 and respectively extending into the pistons 17, and 75 respectively located in the longitudinal centers of said pistons, are two driving shafts 20, each of which is provided with spiral driving means, which may comprise a peripheral spiral groove 21.

Respectively rotatably mounted in the cylinders 1 are two ring driving members 22, which respectively encircle the driving shafts 20, and in each of which are rotatably seated two balls 23, Figs. 5 to 9, which are mounted in and have traveling engagement with the grooved portions 21 of the shafts 20.

Respectively secured on the lower ends of the driving shafts 20 are two bevel gear wheels 24, which respectively mesh with bevel gear wheels 25, of corresponding diameters to the wheels 24, and which are secured on the driven shaft 15. The latter has secured on it a sprocket wheel 26, which is connected by a chain belt 27 with a sprocket 90 wheel 28 secured on the crank shaft 13 and of twice the diameter of the sprocket wheel 26.

When either piston 17 moves downwardly, it will carry with it the adjacent driving ring 100

member 22, the balls 23 of which, by engaging the adjacent driving shaft 20 in the right hand spiral groove 21, will cause the shaft 20 to turn counter-clockwise, as viewed from above, the ring member 22 being held from 5 rotation, on the downward movement of the piston, by a pawl or clutch member 29 having on its upper side a tooth 30, which is adapted to enter a recess 31 in the lower side of the ring member 22. The disposition of 10 the tooth 30 and recess 31 is such that the ring member 22 is held by the pawl 29 from turning clockwise, as viewed from above, but can rotate counter-clockwise, when the piston moves upwardly.

15 The pawl 29 has at its lower end a stem 32, which is vertically slidable in a vertical hole in the piston, Fig. 3.

20 Encircling the stem 32 is a coil spring 33, the lower end of which bears on the piston 17, and the upper end of which bears against the under side of the pawl 29 and normally forces the pawl into engagement with the ring member 22. The pawl 29 has opposite 25 flat vertical sides which slidably engage opposite sides of a recess 34 in the piston, whereby the pawl is held from turning.

25 With the spiral groove 21 of each piston having a lead, as shown, such that with a full 30 down stroke of the piston, the adjacent shaft 20 will make one complete revolution, and with the gear wheels 24 and 25 of like diameters, and the sprocket wheel 28 twice the diameter of the sprocket wheel 26, the driven 35 shaft 15 will make two complete revolutions to one revolution of the crank shaft 13 and one full reciprocation of the piston 17, whereby without increasing the piston speed, the speed of the machine driven by the shaft 15 may be doubled.

40 The cranks 19 of the crank shaft 13, in a two cylinder engine, as shown, are disposed diametrically opposite to each other, so that when one piston 17 is moving in one direction, the other piston will be moving in the 45 opposite direction. The function of the crank shaft 13 is to force the pistons upwardly on the exhaust strokes and downwardly on the intake strokes. When either cylinder has 50 a charge fired in it, the piston in said cylinder will be forced by the explosion downwardly, in the usual manner, and through, the intermediary of the crank shaft 13, it will force the other piston upwardly.

55 When the pistons 17 move upwardly the shafts 20 will rotate the ring members 22 counter-clockwise, as viewed in Fig. 3 from above, the springs 33 yielding to permit the pawls 29 to be moved downwardly by the ring members 22 during such direction of 60 rotation of the latter.

35 designates two usual spark plugs with which the cylinders may be provided respectively.

65 Any usual type of timing mechanism, not

shown, may be connected to and operated by the crank shaft 13.

70 While I have shown an engine having two cylinders, it will be obvious that this number may be varied.

I do not limit my invention to the structure shown and described, as many modifications, within the scope of the appended claims, may be made without departing from the spirit of my invention.

75 What I claim is:

1. In an explosive engine the combination with a reciprocative piston and a rotary shaft having spiral driving means, of a ring driving member reciprocative with and rotative relatively to said piston and longitudinally movable on and having driving engagement with said shaft and having in one end a recess, a pawl having a stem longitudinally slidably fitted in said piston, said pawl being held from rotation in and by said piston and being adapted to enter said recess for holding said ring member from rotation in one direction, when said piston is moving on its power stroke, and adapted to be forced out of said recess by said ring member, when said piston is moving in the opposite direction, and resilient means for normally forcing said pawl into locked engagement with said ring member.

2. In an explosive engine the combination with a reciprocative piston and a rotary shaft having spiral driving means, of a ring driving member reciprocative with and rotative relatively to said piston and longitudinally movable on and having driving engagement with said shaft, a pawl longitudinally slidably fitted in and held from rotation by said piston and having means adapted to engage and hold said ring member from rotation in one direction when said piston is on its power stroke and forced by said ring member from such engagement when the piston is moving in the opposite direction, and resilient means bearing on said piston and against said pawl for normally forcing said pawl to a position in which the pawl is adapted for such holding engagement.

110 In testimony whereof I have signed my name to this specification.

115 CHARLES A. LEE.
